UNITED STATES PATENT OFFICE

PETER STAY, OF REEDLEY, CALIFORNIA

MAIL BOX

Application filed June 20, 1929. Serial No. 372,483.

This invention aims to provide a mail box which can be manufactured cheaply out of sheet metal, novel means being provided for hingedly mounting the front of the box, and 5 novel means being supplied for holding the front in opened and in closed positions.

It is within the province of the disclosure to improve generally and to enhance the utility of devices of that type to which the present invention appertains.

With the above and other objects in view, which will appear as the description proceeds, the invention resides in the combination and arrangement of parts and in the details of 15 construction hereinafter described and claimed, it being understood that changes may be made in the precise embodiment of the invention herein disclosed, within the scope of what is claimed, without departing 20 from the spirit of the invention.

In the accompanying drawing:

Figure 1 shows in front elevation a device constructed in accordance with the invention;

Figure 2 is a bottom plan;

Figure 3 is a vertical transverse section;

Figure 4 is a detail enlarged from Figure 3.

The mail box forming the subject matter of this application comprises a body 1 including a bottom part having terminal sockets 7 and intermediate sockets 9 spaced from each other and from the terminal sockets 7.

A hinge rod 8 is mounted in the sockets 7-9. The mail box includes a front 10 pro-

vided with terminal eyes 15 and with an intermediate eye 16. The terminal eyes 15 are engaged around the hinge rod 8 between the terminal sockets 7 and the intermediate sockets 9.

The intermediate eye 16 is engaged around the hinge rod 8 between the intermediate sockets 9. A reinforcing rod 18 is ex-

tended along the inner edge of the front 10. The front 10 has projections 17 extended around the reinforcing rod 18 and located

between the terminal eyes 15 and the intermediate eye 16. The projections 17 are curved and prolonged to form tongues 19 extended

part around the intermediate sockets 9. The projections 17 and the reinforcing rod 18 form an eccentric shoulder 22 which engages

a portion of the bottom 5 to limit the opening of the front 10.

The device is further characterized by the fact that the tongues 19 and the intermediate sockets 8 are provided with lug and seat elements 20-21 which interengage to hold the front 10 closed.

The body 1 includes a top 2, a back 3, and ends 4. The free edges of the body may be provided with reinforcements wherever 60 needed, and the lid or front 10 is supplied at its upper edge with a reinforcing bead 11 which extends beneath the top 2, in engagement therewith, preferably, when the front 10 is closed as shown in Figure 3. The front 10 is supplied at its ends with prolonged side wings 12 located closely adjacent to the ends 4 of the body 1.

When the front 10 is opened, as shown in dotted line in Figure 3, the lower inner corners of the wings 12 remain between the ends 4 of the body 1, when the lid or front 10 is opened as far as it will go, it being recalled that the opening movement of the lid or front 10 is limited by engagement between 75 the shoulder 22 and the portion of the bottom 5, as indicated in dotted line in Figure 3.

The device is simple in construction, and will afford a protection for mail matter and the like. For the convenient manipulation of 80 the lid or front 10, it may be provided with a handle 14.

I claim:

A receptacle comprising a body including a bottom having terminal sockets and intermediate sockets spaced from each other and from the terminal sockets, a hinge rod in the sockets, a front provided with terminal eyes and with an intermediate eye, the terminal eyes being engaged around the hinge rod between the terminal sockets and the intermediate eye being engaged around the hinge rod between the intermediate sockets, a reinforcing rod extended along the inner edge of the front, the front having projections extended around the reinforcing rod and located between the terminal eyes and the intermediate eye, the projections being curved and prolonged to form tongues extended part way 100 around the intermediate sockets, the projec-

tions and the reinforcing rod forming an eccentric shoulder which engages a portion of the bottom to limit the opening of the front, the tongues and the intermediate sockets being provided with lug and seat elements which interengage to hold the front closed.

In testimony that I claim the foregoing as my own, I have hereto affixed my signature.

PETER STAY.
